UNITED STATES PATENT OFFICE.

JAMES A. GIESE, OF CHICAGO, ILLINOIS, ASSIGNOR TO THE ADAMS & WESTLAKE COMPANY, OF CHICAGO, ILLINOIS, A CORPORATION OF ILLINOIS.

SLIDING-DOOR LATCH.

1,003,896.

Specification of Letters Patent. Patented Sept. 19, 1911.

Application filed June 14, 1911. Serial No. 633,050.

To all whom it may concern:

Be it known that I, JAMES A. GIESE, a citizen of the United States, and resident of Chicago, county of Cook, and State of Illinois, have invented certain new and useful Improvements in Sliding-Door Latches, of which the following is a specification, and which are illustrated in the accompanying drawings, forming a part thereof.

10 The invention relates to latches for sliding doors, its objects being to provide a latch the controlling handle of which may be locked independently of the latching member and in connection with which a latching member is provided for securing the door in open position and which is controllable by the handle when the latter is or is not locked with reference to its relation to the forward latching member.

20 An embodiment of the invention is fully hereinafter described and is illustrated in the accompanying drawings in which—

Figure 1 is a detail elevation of a door and its casing provided with the improved latch, the keeper mechanism for the forward or closing latch being shown in section; Fig. 2 is a vertical section, partly in elevation of the latch casing; Fig. 3 is a detail inside elevation of one of the faces of the casing of the latch, the controlling spindle being shown in section, and Fig. 4 is a sectional view on the line 4—4 of Fig. 3.

30 The door is represented at 10, the forward jamb of the casing at 11 and the rearward jamb at 12. The latch proper is inclosed within a casing 13 mortised into the forward edge of the door and being provided with a face plate 14 through which securing screws may be set. Face plates 15, 16, are applied to the sides of the door and within them there is journaled the controlling spindle 17 which passes through the casing 13 and carries at each end a handle 18, 19 which preferably project upwardly.

40 The latching member for securing the door when closed takes the form of a hook 20 located within the casing 13 and pivoted upon a stud 21 set in the side walls thereof. A spring, as 22, fixed upon a stud 23 set in 50 the walls of the casing bears downwardly upon the hook 20 and normally holds it against a stop 24. The swinging end of the hook lies entirely within the casing and is inclined or rounded in order that it may be 55 forced upwardly against the resistance of

the spring 22 by its engagement with the keeper.

The keeper 25 takes the form of a reciprocal bolt having a hook or shoulder 26 adjacent its forward end, this bolt being 60 housed within a casing 27 mortised into the jamb 11, the keeper normally being retracted so that its forward end does not project beyond the face of the casing. A plunger 28 is mounted in the casing 27 and normally 65 projects beyond its forward face. A lever 29 pivoted within the casing 27 engages shoulders upon the keeper and upon the plunger so that these two members move simultaneously but in opposite directions. A 70 spring 30 normally holds the plunger in its advanced and the keeper in its retracted position. When the door is closed its forward edge forces the plunger 28 inward, thus advancing the keeper and causing its engagement with the hook 20. A follower arm 75 31 fixed upon the spindle 17 bears upwardly against the hook 20. Pressure upon either of the handles 18, 19 which tends to urge the door open turns the spindle and thus 80 raises the hook 20 out of engagement with the keeper.

An arm or shoulder 32 projects downwardly from the hub of the follower 31 and a locking bolt 33 slidably mounted upon one 85 of the side plates, as 15, may be projected into the path of the arm or shoulder 32 thereby locking the handles 18, 19 against movement in the direction necessary for raising the hook. The bolt 33 is provided with a shoulder 34 for engagement by a key (not shown) which may be inserted through the key hole 35. Suitable tumblers, as 36, may be provided for preventing the use of other than the key specially adapted to the lock. A 90 hook 37, here shown as in loop form, is provided for securing the door in its open position and co-operates with a keeper 38 in hook form secured to the jamb 12. The hook or loop 37 is loosely pivoted upon the spindle 100 17 adjacent one of its ends and outside of the face plate, as 16, and is provided with a shoulder 39 for engagement by a stud 40 projecting from the hub of the adjacent handle, as 19, whereby the hook or loop 37 105 is raised when the handle is moved in the direction which tends to close the door. A spring 41 is provided for normally holding the hook or loop 37 in its lower or advanced position. This spring may be con- 110

veniently attached to a stud 42 on the inner face of the plate 16 and engaging the hook or latch 37 through the medium of a stud 43 formed thereon and projecting through a 5 segmental slot 44 in the plate 16. The handles are held in central position by the spring 22 and a spring 45, here shown as formed integral with the spring 22, which bears downward on a swinging arm 46 piv- 10 oted on the stud 21 and engaging a rearwardly projecting arm 47 of the follower 31. The arm 46 oscillates between stops 48, 49, resting upon the latter and the hook 20 resting upon the stop 24 when the handles 15 are in central position.

Movement of the handles and consequently of the spindle in either direction has the effect of raising one of the hooks 20 and 37, without acting upon the other. When the 20 bolt 33 is advanced by the key it prevents the movement of the spindle in the direction necessary to raise the hook 20 but leaves it entirely free to move in the opposite direction for raising the hook 37. This locking 25 mechanism, however, has no effect upon the hook 20, leaving it free to move upward when it comes into engagement with the keeper 25 as the door is closed. The locking bolt may, therefore, be thrown at 30 any time, when the door is open or closed. The latch is primarily designed for use in connection with car doors. It is customary to lock the doors of cars when they are not in use. The attendant often finds it necessary 35 to work rapidly and this latch will permit him to go through a train of cars and throw the locking bolts in their doors while the latter remain open, permitting the passengers to leave the cars at their leisure. 40 When the cars are emptied the doors may be closed and cannot be opened without the use of the key. This closing of the doors is not in the slightest interfered with by the fact that the bolt is thrown as the hook 37 45 may be disengaged from its keeper by merely turning the spindle in the required direction and the hook 20 will automatically engage its keeper as the door makes contact with the jamb 11.

50 I claim as my invention—

1. In a door latch, in combination, a cas-
ing, a spring actuated latching element piv-

oted to the casing, a spindle projecting through the casing, a handle fixed to the spindle, a follower fixed to the spindle and engageable with the latching element to retract the same, a lateral shoulder on the follower, and a bolt movable into the path of the shoulder. 55

2. In a door latch, in combination, a for- 60 wardly projecting spring actuated latching element, a rearwardly projecting spring actuated latching element, such two elements being independently movable, an oscillatable spindle having a handle fixed thereto and adapted to retract such latching elements respectively, when moved in opposite direc- 65 tions.

3. In a door latch, in combination, a for- 70 wardly directed spring advanced pivoted latch, a rearwardly directed spring actuated pivoted latch, an oscillatable spindle for retracting such latches independently, and a lock for holding the spindle against movement in one direction only. 75

4. In a door latch, in combination, a for- 80 wardly directed spring advanced pivoted latching element, an oscillatable spindle, a follower fixed upon the spindle and engageable with the latch to move it in opposition to the spring, a rearwardly directed spring actuated latch loosely pivoted upon the spindle and a shoulder on the spindle engageable with the rearwardly projecting latch to move it in opposition to its spring. 85

5. In a door latch, in combination, a for- 90 wardly directed spring advanced pivoted latching element, an oscillatable spindle, a follower fixed upon the spindle and engageable with the latch to move it in opposition to the spring, a rearwardly directed spring actuated latch loosely pivoted upon the spindle, a shoulder on the spindle engageable with the rearwardly directed latch to move it in opposition to its spring and a 95 locking bolt engageable with the spindle for holding it against action upon the forwardly directed latch, the spindle being free to move to act upon the rearwardly directed latch.

JAMES A. GIESE.
